APPARATUS FOR THE PRODUCTION OF
BROKEN FILAMENT YARNWilliam Charles Hanse, Philadelphia, Pa., as-
signor to American Viscose Corporation, Marcus
Hook, Pa., a corporation of Delaware

Application December 1, 1939, Serial No. 307,004

13 Claims. (Cl. 19—1)

This invention relates to improvements in methods and apparatus for the production of broken filament yarn.

The present invention has for its principal object to provide improved methods and apparatus for the production of broken filament yarn from yarn comprising continuous filaments.

Other objects and advantages will be apparent from the following description and accompanying drawing in which suitable forms of apparatus embodying the invention are shown.

Figure 1 is a view of an embodiment of the invention applied to a down twister.

Figure 2 is a view of a modification of the embodiment of the invention shown in Figure 1.

Figure 3 is a view of another modification of the embodiment of the invention shown in Figure 1 that is provided with means whereby the yarn may be subjected to successive abrading operations.

Figure 4 is a view of a further modification of the embodiment of the invention shown in Figure 1 that is provided with a plurality of abrading means whereby the yarn may be subjected to successive abrading operations.

In accordance with the present invention yarn comprising continuous filaments is passed over a freely revolvable tapered abrading means that may be either conical or conoidal and having an abrasive surface. Filaments of the yarn engage in the abrasive surface and cause the abrasive means to revolve. The yarn tends to travel around with the abrasive means in a direction lying in a plane at right angles to the axis of the abrasive means as indicated by the dotted lines in the drawing. The yarn is withdrawn from the abrasive means in a lateral direction extending at an angle to the path of travel of the yarn on the abrasive means, and toward the larger end of the abrasive means, causing certain filaments to be broken. This lateral direction lies in a plane disposed at an angle less than a right angle to the axis of the abrasive means. The extent of the breaking of the filaments and the appearance of the resulting yarn depend upon the angle at which the yarn is withdrawn. Accordingly means are provided whereby this angle may be varied so that yarns of different character may be produced.

While the invention is shown and described as applied to a twisting machine it is to be understood that the invention may be used with any type of apparatus wherein yarn travels between two points.

The invention is shown in Figure 1 as applied

5 to a down twister. In this figure, reference character 1 indicates yarn comprising continuous filaments passing from the stationary supply bobbin 2 to the take-up bobbin 3. The rate of travel of the yarn is determined by the feed rollers 4. The ring traveler 5 arranged on the ring twister 6 carried by the traverse member 1 cooperates with the take-up bobbin to impart a twist to the yarn. The traveling yarn passes over the 10 abrasive means comprising the tapered roller 8 of abrasive material or having an abrasive surface, mounted to revolve freely on the shaft 9. Rollers having various degrees of taper may be used depending on the character of the yarn and 15 the extent of the abrasive action desired. The yarn is directed onto the roller by the upper guide 10 and is withdrawn by the lower guide 11. The lower guide is so positioned that the yarn is withdrawn from the roller in a lateral direction 20 extending at an angle to the path of travel of the yarn on the roller and toward the larger end of the roller. The position of the lower guide, and therefore the angle at which the yarn is withdrawn, may be readily varied by means not 25 shown which would be obvious, so that the extent of breaking of the filaments may be changed and yarns of different character and appearance may be produced.

30 A modification of the abrasive means is shown in Figure 2. The abrasive means is the same as that shown in Figure 1 and comprises the tapered roller 12 of abrasive material or having an abrasive surface, mounted to freely revolve on the shaft 13. The yarn 16 comprising continuous 35 filaments is directed onto the roller by the guide 14 and is withdrawn by the guide 15. However the axis of the roller is disposed at an angle to the path of travel of the yarn being withdrawn from the roller so that the yarn is withdrawn in a lateral direction extending at an angle to the 40 direction of its path of travel on the roller and toward the larger end of the roller. Filaments of the yarn on being withdrawn from the roller are broken the same as in the form of invention shown 45 in Figure 1. The angle at which the axis of the roller is disposed may be varied by means not shown but which would be obvious, so that the extent of breaking of the filaments may be changed and different types of yarn may be produced.

50 Another modification of the invention is shown in Figure 3. The abrasive means shown in this figure is the same as the abrasive means that is shown in Figure 1 and comprises the tapered roller 17 of abrasive material or having an abra-

sive surface, mounted to freely revolve on the shaft 18. However in this form of the invention means are provided whereby the yarn 19 comprising continuous filaments may be subjected to a succession of abrading operations. The yarn is directed onto the rollers by the guide 20 and is withdrawn by the guide 21 in a lateral direction extending at an angle to the path of travel of the yarn on the roller toward the larger end of the roller. The yarn is directed back onto the roller and is also withdrawn by the guide 22 in a lateral direction extending at an angle to the path of travel of the yarn on the roller toward the larger end of the roller. The position of each of the guides 21 and 22 may be varied by means not shown which would be obvious so that the extent of breaking of the filaments during each passage over the roller may be varied.

A further modification of the invention is shown in Figure 4. Each of the abrasive means shown in this figure is the same as the abrasive means shown in Figure 1. This modification comprises the tapered rollers 23 and 24 of abrasive material or having an abrasive surface, mounted to freely revolve on the shafts 25 and 26. Yarn 30 comprising continuous filaments is directed onto the roller 24 by the guide 27 and is withdrawn from the roller by the guide 28 in a lateral direction extending at an angle to the path of travel of the yarn on the roller toward the larger end of the roller. The yarn is directed by the guide 28 to the roller 23 and is withdrawn by the guide 29 in a lateral direction extending at an angle to the path of travel of the yarn on the roller toward the larger end of the roller. The position of each of the guides 28 and 29 may be varied by means not shown which would be obvious so that the extent of breaking of the filaments during the passage over each roller may be varied. Although only two rollers have been shown in this modification more rollers may be used if desired.

While preferred embodiments of the invention have been shown and described it is to be understood that changes and variations may be made without departing from the spirit and scope of the invention as defined by the claims.

What I claim is:

1. An apparatus for producing broken filament yarn comprising a revolvable tapered abrasive roller, means for directing a traveling yarn onto the roller and means for withdrawing the yarn from the roller in a lateral direction extending at an angle to the path of travel of the yarn on the roller toward the larger end of the roller.

2. An apparatus for producing broken filament yarn comprising a freely revolvable tapered abrasive roller, means for directing a traveling yarn onto the roller and means for withdrawing the yarn from the roller in a lateral direction extending at an angle to the path of travel of the yarn on the roller toward the larger end of the roller.

3. An apparatus for producing broken filament yarn comprising a revolvable tapered roller having an abrasive surface thereon, means for directing a traveling yarn onto the roller and means for withdrawing the yarn from the roller in a lateral direction extending at an angle to the path of travel of the yarn on the roller toward the larger end of the roller.

4. An apparatus for producing broken filament yarn comprising a revolvable tapered abrasive roller, means for directing a traveling yarn onto the roller, means for withdrawing the yarn from

the roller in a lateral direction extending at an angle to the path of travel of the yarn on the roller toward the larger end of the roller, said yarn withdrawal means being adjustable so as to vary the angle at which the yarn is withdrawn from the roller.

5. An apparatus for producing broken filament yarn comprising a revolvable tapered abrasive roller, means for directing a traveling yarn onto the roller, means for withdrawing the yarn from the roller in a lateral direction extending at an angle to the path of travel of the yarn on the roller toward the larger end of the roller and means for varying the angle at which the yarn is withdrawn from the roller.

10 6. An apparatus for producing broken filament yarn comprising a tapered abrasive member, means for directing a traveling yarn onto the member and means for withdrawing the yarn from the member in a lateral direction extending at an angle to the path of travel of the yarn on the member and toward the larger end of the member.

15 7. An apparatus for producing broken filament yarn comprising a revolvable tapered abrasive roller, means for passing a yarn over the roller, the axis of said roller being disposed at an angle to the path of the traveling yarn, means for directing the yarn onto the roller and means for withdrawing the yarn from the roller in a direction extending at an angle to the direction of travel of the yarn on the roller toward the larger end of the roller.

20 8. An apparatus for producing broken filament yarn comprising a revolvable tapered abrasive roller, means for passing a yarn over the roller, the axis of said roller being disposed at an angle to the path of the traveling yarn, means for directing the yarn onto the roller and means for withdrawing the yarn from the roller in a direction extending at an angle to the direction of travel of the yarn on the roller toward the larger end of the roller and means for varying the angle at which the roller is disposed.

25 9. An apparatus for producing broken filament yarn comprising a revolvable tapered abrasive roller, means for directing a traveling yarn onto the roller, means for withdrawing the yarn from the roller in a lateral direction extending at an angle to the path of travel of the yarn on the roller toward the larger end of the roller and for redirecting the yarn back onto the roller and means for again withdrawing the yarn from the roller in a lateral direction extending at an angle to the path of travel of the yarn on the roller toward the larger end of the roller.

30 10. An apparatus for producing broken filament yarn comprising a revolvable tapered abrasive roller, means for directing a traveling yarn onto the roller, means for withdrawing the yarn from the roller in a lateral direction extending at an angle to the path of travel of the yarn on the roller toward the larger end of the roller and for redirecting the yarn back onto the roller and means for again withdrawing the yarn from the roller in a lateral direction extending at an angle to the path of travel of the yarn on the roller toward the larger end of the roller, said 35 yarn withdrawal means being adjustable so as to vary the angle at which the yarn is withdrawn from the roller.

40 11. An apparatus for producing broken filament yarn comprising a plurality of tapered revolvable abrasive rollers, means for directing a

45 50 55 60 65 70 75

traveling yarn onto each of the rollers and means for withdrawing the yarn from each of the rollers in a lateral direction extending at an angle to the path of travel of the yarn on the rollers toward the larger end of the rollers.

12. An apparatus for producing broken filament yarn comprising a revolvable tapered abrasive roller, means for directing a traveling yarn onto the roller and means for withdrawing the yarn from the roller in a lateral direction ex- 10

tending at an angle to the path of travel of the yarn on the roller.

13. An apparatus for producing broken filament yarn comprising a revolvable tapered roller having an abrasive surface thereon, means for directing a traveling yarn onto the roller and means for withdrawing the yarn from the roller in a lateral direction extending at an angle to the path of travel of the yarn on the roller.

WILLIAM CHARLES HANSE.
